Primary Examiner — Philip S Hyder*Assistant Examiner* — Cary M Robinson(74) *Attorney, Agent, or Firm* — NSIP Law(57) **CLAIM**

We claim the ornamental design for a display screen or portion thereof with icon, as shown and described.

DESCRIPTION

FIG. 1 is a front view of a first embodiment of a display screen or portion thereof with icon showing our new design; and,

FIG. 2 is a front view of a second embodiment of a display screen or portion thereof with icon showing our new design. The dot-dash lines in the figure show a display screen or portion thereof and form no part of the claimed design.
